his Atty.

UNITED STATES PATENT OFFICE

FRIEDRICH DUWE, OF MAINZ, GERMANY, ASSIGNOR TO MASCHINENFABRIK AUGSBURG-NURNBERG A. G., OF NUREMBERG, GERMANY, A CORPORATION OF GERMANY

ROLLER WEIR WITH EXTENSION GATE

Application filed January 25, 1928, Serial No. 249,322, and in Germany August 18, 1927.

My invention relates to an improvement of devices for erecting and laying down extension gates provided on the drum-bodies of drum-weirs. The device according to this invention has the advantage of being of especial simplicity and great stability, as compared with the construction described in my co-pending application for patent Ser. No. 165,740.

10 The present invention consists in this that within the drum body which forms the gate of the weir there is provided a lever mechanism or similar contrivance, co-axial with said drum-body and the parts of the chain 15 passing around said drum body, the arms of said lever mechanism projecting through the wall of the drum-body in such a manner that at least one of said arms will be in engagement with the slidingly arranged chain in 20 every position of said drum-body, while the motion of said chain during condition of no-load is transmitted by means of a system of levers to said device.

In the accompanying drawing showing an 25 embodiment of the present invention in connection with a drum-weir;

Fig. 1 is a side elevation of a drum-weir and gate, Fig. 2 a section through one end of the weir-drum, and Fig. 3 a top plan view of 30 Fig. 1.

As shown in the drawing, the endless chain *b* is operated by means of the pinion *a* of a winch and carried around the drum-body *d* by means of guiding members *c*, Fig. 2. In 35 the lowered position of the drum *d* the chain *b* is released from the load of the weir and may slide around the drum-body between the guiding members *c*.

Co-axially to the drum *d* and the parts of 40 the chain passing around the latter, there is provided a two-arm lever or similar body, having arms *1^a* and *1^b* projecting through slots provided in the wall of the drum *d*. The arm *1^b* of this lever, being downwardly directed in the closing position of the drum *d*, is in engagement with the chain *b* while the arm *1^a* is out of engagement and arranged in such a manner that it comes into engagement 45 with the chain *b* after the extension gate *k* has been laid down or after the drum-body *d*

has been turned to a certain angle, before the arm *1^b* is withdrawn from engagement with said chain *b*. A further lever *4* is mounted upon the hub of the two-arm lever, said lever *4* being connected with the movable extension gate *k*, provided on the drum *d*, by means of the link *5*.

The chain *b* is further provided with a stop *m* at a point between the pinion *a* of the winch and a guiding roller *r* which is provided in the rear of said winch, said stop co-operating with fixed abutments *o* and *p*. A suspension device *q* of well known kind is provided for suspending said chain *b* in a plurality of parts, as indicated in Fig. 1, 55 said parts being wound up during the lifting of the drum *d*. However, the parts thus far described do not constitute the subject matter of the present invention.

The mode of operation of the weir and the device for erecting and laying down the movable extension gate *k* is as follows: In 60 order to lay down the movable extension gate *k*, the winch is caused to rotate as indicated by the arrow at the upper part of the drawing. By means of the chain *b* which passes around the drum *d* at the ends thereof in sliding engagement therewith the lever mechanism *1^a—1^b* is caused to rotate in the direction as indicated by the arrow, so that 65 the movable extension gate *k* will be laid down by the said lever-and-rod-system *4, 5*. If it is desired to raise the drum *d*, the operation of the winch is continued, so that the drum body *d* will be lifted, the locking member *m* provided on the chain having come in the meanwhile into engagement with the stop *p*. The arm *1^b* has now been withdrawn 70

from engagement with the chain *b*, the arm *1^a* having previously come into engagement with the chain *b*. In the raised position of the drum *d*, the several parts will be in a position as indicated in dotted lines in the drawing. During the lowering of the drum *d* and during the erection of the extension gate *k* the motions of the several parts will 75 be reversed.

The shape of the two-arm lever *1^a—1^b* may 80 of course also be different from that shown in the drawing, and the two arms *1^a* and 85 *1^b*

1^b of said lever may also be arranged to form a greater angle with each other than shown. It is only required that the arm 1^b be not withdrawn from engagement with the chain b before the arm 1^a is in engagement with the chain and vice versa.

5 I claim:

10 1. In combination with a drum weir, a drum-body, an extension gate hinged thereto, a chain adapted to pass around said drum-body in sliding engagement therewith, a two-arm lever pivotally mounted within said drum-body, at least one arm of said lever being in engagement with said chain, and

15 2. a second lever adapted to transmit the motion of said chain when in condition of no-load to said extension gate.

20 2. In combination with a drum weir, a drum-body, an extension gate hinged thereto, a winch, a chain passing around said drum-body in sliding engagement therewith and adapted to be operated by said winch, a two-arm lever pivoted within said drum-body coaxially therewith, at least one arm

25 of said lever being in engagement with said chain, and a second lever adapted to transmit the motion of said chain when in condition of no-load to said extension gate.

In testimony whereof I affix my signature.

30

FRIEDRICH DUWE.
